UNITED STATES PATENT OFFICE.

WALTER BENJAMIN HARPER, OF LAKE CHARLES, LOUISIANA.

DISTILLING APPARATUS.

SPECIFICATION forming part of Letters Patent No. 789,691, dated May 9, 1905.

Application filed July 22, 1904. Serial No. 217,663.

To all whom it may concern:

Be it known that I, WALTER BENJAMIN HARPER, a citizen of the United States, and a resident of Lake Charles, in the parish of Calcasieu and State of Louisiana, have invented a new and Improved Distilling Apparatus, of which the following is a full, clear, and exact description.

The object of the invention is to provide a new and improved apparatus, more especially designed for the manufacture of turpentine, acetic acid, wood-alcohol, tar, charcoal, wood-pulp, &c., by the destructive distillation of wood, coal, or other organic or inorganic matter containing any or all of the products mentioned, the apparatus being simple and durable in construction and arranged to readily separate the volatile matter and oils from the wood and to separate the solid matter or fibers from the tar.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a longitudinal central sectional elevation of the same. Fig. 3 is an end elevation of the same. Fig. 4 is a transverse section of the same on the line 4 4 of Fig. 2, and Fig. 5 is a longitudinal central section of the improvement as arranged for the production of turpentine.

In the brickwork A of the furnace is formed a heating-chamber A', through which extends a retort-shell B, closed at the ends by fixed heads B' and B'', secured to suitable supports B' B'', arranged outside of the brickwork, as plainly illustrated in the drawings.

The retort-shell B is rotated, and for this purpose the shell extends beyond the ends of the brickwork A, and on the outer ends of the shell are secured gear-wheels C, in mesh near their lower ends and on opposite sides with pinions C', (see Fig. 1,) of

which the pinions on each side of the retort-shell are secured on a shaft C², journaled in suitable bearings and provided at its forward end with a bevel gear-wheel C³, in mesh with a bevel gear-wheel C⁴, secured on a transverse shaft C⁵, journaled in suitable bearings and provided with a pulley C⁶, connected by a belt with other machinery for imparting a rotary motion to the shaft C⁵. By the bevel gear-wheels C⁴ C³ the shafts C² on the sides of the retort are rotated, so that the pinions C' secured on the said shafts, rotate the gear-wheel C, and hence revolve the retort-shell B.

A feed device is held on the head B' to feed the material to be treated into the retort-shell, the said feed device being provided with a conveyer-casing D, in which is mounted to revolve a conveyer-screw E, the outer end of the casing having an inlet-chute D', into which the wood is dumped, preferably in a reduced state, so that the conveyer-screw E feeds the reduced wood into the inlet end of the retort-shell B.

In order to feed the material dropped into the inlet end of the retort-shell B toward the discharge end thereof, a chain F is provided, secured at one end only to the conveyer-casing D, the other end being free, the chain extending loosely longitudinally along the bottom of the shell B, so that when the latter is rotated and the reduced wood is fed into the shell, as previously described, then the chain F is caused to wriggle, thereby feeding the material from the inlet end of the shell toward the discharge end thereof—that is, toward the head B'. It is understood that as the reduced wood is lighter than the links of the chain and the retort is revolving the chain by its wriggling motion feeds the wood rearward, as described.

In the head B' is secured a conveyer-casing G, containing a conveyer-screw H and having a trough-like inner end G', extending centrally into the shell B at the discharge end thereof, and the bottom of the trough G' is provided with perforations G² to allow the tar carried into the trough G' to flow through the perforations back into the discharge end of the shell at the head B'. The inner terminal

of the trough-like end G' is closed to prevent the material from falling back into the retort-shell.

In order to carry the material fed by the 5 chain F toward the discharge end of the retort-shell up into the trough G', the interior of the retort-shell is provided with a number of radially-disposed wings I at the discharge end of the shell, so that the material passing 10 to a wing is carried up by the latter as the retort-shell rotates, and finally slides off the wing as the latter nears an uppermost position and drops into the trough G', in which the material is fed outwardly by the conveyer-screw H, and the tar is allowed to drop through the perforations G², as previously explained.

The conveyer-screw H has its shaft H' provided with a pulley H², connected by a belt with other machinery for imparting a rotary 20 motion to the conveyer-screw, and the said shaft H' may be extended lengthwise through the shell B to connect with the shaft of the conveyer-screw E, so as to rotate the conveyer-screw H and E in unison and from the same 25 source.

The outer end of the conveyer-shell G for the discharging device is provided with a chute G³ for carrying off the fiber, and from the bottom of the said casing G extends a branch pipe 30 J, having a valve J' for connecting or disconnecting the branch pipe J with or from the conveyer-casing G. The branch pipe J leads to the casing K of a pressing device containing sets of rollers K', between which passes 35 the material to be pressed, so as to press the tar out of the wood fibers, the fibers then passing from the last set of rollers K' into a chute K², discharging the fibers to a car or other suitable receptacle held below the chute K².

40 In order to insure a proper feed of the fibers through the chute K², the latter is provided with a set of revolving feed-rollers K³, as plainly indicated in Fig. 2. From the hopper-shaped bottom of the casing K of the pressing device leads a pipe K⁴, having a valve K⁵, to a tank L for receiving the tar, the said tank L being also connected by a pipe N, having a valve N', with the bottom of the head B², so that the tar separated from the material within 45 the shell B and flowing from the perforations G² can pass by way of the pipe N into the tank L.

Through the head B² extends a steam-pipe O, connected with a boiler or other suitable 55 source of steam-supply, to furnish steam for the material under treatment in the retort-shell. The head B² is provided near its upper end with an outlet-pipe P for carrying off the volatile matter to a suitable condenser, 60 and a similar pipe Q leads from the upper end of the head B² to carry off the heavy oils, as hereinafter more fully described, the said pipes P and Q being provided with suitable valves P' and Q' to allow of opening and closing the pipes.

The furnace A for furnishing the necessary heat for the heating-chamber A' to heat the retort-shell and its contents is arranged as follows: The fire-box A² for burning coal, oil, gas, or like fuel is connected with a combustion-chamber A³ over a bridge-wall A⁴, and the rear end of the said combustion-chamber is closed by a transverse partition A⁵, spaced from the rear end wall of the furnace. Each side of the combustion-chamber A³ is connected by a port A⁶ with a duct A⁷, arranged lengthwise in the heating-chamber A' above an arch A⁸, separating the fire-box A² and the combustion-chamber A³ from the said heating-chamber A'. The arch A⁸ is supported at its rear end by the partition A⁵, which is extended upward a sufficient distance to also close the rear ends of the ducts A⁷, which open at their forward ends into the front end of the heating-chamber A'. The rear end of the 85 heating-chamber A' is connected at the bottom with a downwardly-extending duct A⁹, connected by a port A¹¹ with a transverse duct A¹⁰, leading to a smoke-stack A¹².

By the arrangement described the products 90 of combustion from the burning fuel in the fire-box A² first pass rearwardly into the combustion-chamber A³ and then by the ports A⁶ into the ducts A⁷, in which the products of combustion travel forwardly to pass into the 95 forward end of the heating-chamber A' to completely surround the retort-shell B. The products of combustion finally pass from the rear end of the heating-chamber A' down into the duct A⁹ and by the port A¹¹ into the 100 duct A¹⁰, from which the products of combustion pass to the smoke-stack, which provides sufficient draft for the products of combustion to travel in the direction above described.

The retort may be rotated continuously or 105 intermittently, and two retorts are employed (see Fig. 5) when the production of not only turpentine, but also of by-products, is desired, and only one retort is required when turpentine alone or when acetic acid and wood-alcohol are to be produced.

The continuous process for the production 110 of turpentine is carried out as follows: The wood is preferably ground in a suitable machine and fed by the conveyer-screw E and casing D into the retort-shell B, in which the wood begins to distil and the resin to exude. The snake-like motion of the chain F causes the material to move toward the wings I as the retort-shell B revolves, and during the time 115 the material is in the shell steam is admitted by way of the pipe O and the shell is heated from the heat emanating from the burning fuel in the fire-box A², as previously described; but the temperature is kept just below the charring-point of the wood. The vapors of light oil and steam arising from the material pass through the pipe P to a condenser, in which they are collected and separated in the usual manner. As the wood continues to en- 120 125 130

ter the retort-shell B the latter fills up and the material which first entered, having reached the wings I, is sufficiently distilled to permit its removal, which is carried out by the wings 5 I lifting the material into the trough G', from which the material is fed outwardly by the conveyer-screw H. The diffused resin or tar in the trough G' drops through the perforations G², as previously explained, to be carried 10 by the pipe N to the tank L. The wood residue carried along the casing G is finally discharged through the chute G³ into a car or other suitable receptacle; but if it desired to make wood fiber then the valve J' is opened 15 to permit the material to pass from the conveyer-casing G into the branch pipe J to pass to the casing K of the pressing device, in which the rolls K' press out any liquid matter contained in the material, and this liquid 20 matter flows by way of the pipe K⁴ into the receiving-tank L. The wood fiber passes from the casing K by way of the chute K² to a car or other device to be carried off to a distant place. If it is desired to complete the distillation, the material instead of being discharged 25 at the chute G³ or passed by way of the branch pipe J to the casing of the pressing device K is carried by the conveyer-screw H directly into another retort-shell B, 30 such as shown in Fig. 5, and heated to a much higher temperature than the one described, so as to drive out the heavy oils still contained in the wood material. In this second retort no steam is used, and the vapors in the tar 35 are carried away the same as in the retort shown in the drawings and described above. In this second retort-shell the wood material is converted into charcoal, which is carried off by the screw-conveyer and is discharged into 40 air-tight cars through a cooler or upon a grate, according to the disposition to be made of the charcoal. The gas from the second retort-shell is either collected in gas-holders or led directly into the fire-box A² to be burned there- 45 in. In the intermittent process the material enters the retort-shell B with or without the use of a feed-screw E, and in this case the retort is filled nearly full, sufficient space being left, however, to prevent clogging of the material. 50 Steam is now turned on by way of the pipe O and the retort is heated from the burning fuel in the fire-box A², as previously explained, so that the temperature of the material contained in the shell B is raised to just below the char- 55 ring-point of the wood. The turpentine-vapor and the steam arising from the material pass through the pipe P and are condensed, as usual, and after the turpentine has been distilled the steam is shut off, the valve P' of the pipe P is closed, and the valve Q' of the pipe Q is opened, so that the vapors of the heavy 60 oils arising from the material in the retort-shell pass to a suitable condenser to be condensed. The tar is discharged from the bot- 65 tom of the shell B by way of the pipe N into the tank L, and when the material in the still has reached a temperature of about 806° Fahrenheit then the operation is complete, it being understood that the temperature within the shell is measured by a suitable pyrometer 70 or similar device. The uncondensable gases pass off with the vapors of the heavy oils and are collected in a tank for further treatment or the said gases are directly burned in the firebox of the furnace. If wood-pulp is to be 75 made, the operation is stopped at a lower temperature. The solid material is removed from the shell B by the wings I and conveyer-screw H, as previously explained, and passed through the pressing-rollers K⁸, and then the retort is 80 recharged for the next operation.

Having thus described my invention, I claim as new and desire to secure by Letters Patent—

1. An apparatus for the destructive distillation of wood and the like, comprising a rev- 85 oluble retort-shell having fixed heads, a fur- nace for exteriorly heating the same, a steam- supply pipe opening into the shell through one of the heads, vapor-outlet pipes leading from the shell at the heads, a liquid-discharge 90 pipe leading from the shell at one of the heads, feeding devices for the shell at one head, a discharge device at the other head, and means carried by the retort for delivering the solid material to the discharge device. 95

2. A distilling apparatus comprising a rev- oluble shell, a heating-chamber surrounding the shell, a feed device for feeding the ma- 100 terial to be heated into one end of the shell, a chain fixed at one end in the forward portion of the retort and extending loosely in the bot- tom of the shell toward the rear end thereof, to feed the material rearward in the shell, a mechanical discharge device in the rear end of the shell, and lifting-plates on the inside of 105 the shell at the rear end thereof and adapted to lift the material up and deliver it to the said mechanical discharge device. 110

3. A distilling apparatus comprising a rev- oluble shell, closed at its ends by fixed heads, and a chain lying in the bottom of the retort and fixed at one end and free at the other end, to feed the material lengthwise in the retort and from the fixed end of the chain toward the loose end thereof. 115

4. A distilling apparatus having a retort formed of a horizontally-disposed revoluble shell and fixed heads, valved vapor-outlet pipes connected with the heads, a feeding-conveyer extending into one end of the shell through 120 one of the heads, a discharging-conveyer lead- ing from the other end of the shell and ex- tending through the other head, a liquid-dis- charge pipe leading from this head at the bot- tom thereof, lifting means in the shell, for 125 carrying the material to the said discharging- conveyer, and feeding means for feeding the material along the bottom of the shell. 130

5. A distilling apparatus having a retort formed of a revoluble shell and fixed heads, a

- feeding-conveyer extending into one end of the shell through one of the heads, a discharging-conveyer leading from the other end of the shell and extending through the other head, 5 a discharge-pipe leading from this head at the bottom thereof, lifting means in the shell for carrying the material to the said discharging-conveyer, and a chain fixed to the feeding-conveyer and extending loosely lengthwise in 10 the bottom of the shell, to feed the material along the shell toward said lifting means.
6. A distilling apparatus comprising a retort formed of a revoluble shell and fixed heads, valved vapor-outlet pipes leading from 15 the said heads, a feeding-conveyer extending into one end of the shell through one of the heads, a discharging-conveyer leading from the other end of the shell and extending through the other head, a liquid-discharge 20 pipe leading from this head at the bottom thereof, lifting means in the shell for carrying the material to the said discharging-conveyer, feeding means for feeding the material along the bottom of the shell, and a press- 25 ing device connected with the said discharging-conveyer for pressing the material, to separate the fibers from the liquid.
7. A distilling apparatus comprising a furnace having a heating-chamber, a retort hav- 30 ing a revoluble shell extending through the heating-chamber, the shell being closed by fixed heads, a delivering-conveyer extending through one head to deliver the material to be treated to the receiving end of the shell, a 35 discharging-conveyer having a trough and a conveyer-screw therein, the trough extending through the other shell-head a distance into the discharge end of the shell, the bottom of the trough being perforated, lifting-plates se- 40 cured to the shell at the discharge end, to lift the material and deliver it to the said trough, and means for feeding the material in the shell from the receiving end to the discharge end.
8. A distilling apparatus comprising a fur- 45 nace having a heating-chamber, a retort hav-

ing a revoluble shell extending through the heating-chamber, the shell being closed by fixed heads, a delivering-conveyer extending through one head to deliver the material to be treated to the receiving end of the shell, a 50 discharging-conveyer having a trough and a conveyer-screw therein, the trough extending through the other shell-head a distance into the discharge end of the shell, the bottom of the trough being perforated, lifting-plates se- 55 cured to the shell at the discharge end, to lift the material and deliver it to the said trough, and means for feeding the material in the shell from the receiving end to the discharge end, the said means comprising a chain fixed at one 60 end to the casing of the delivery-conveyer and extending lengthwise in the bottom of the shell toward the discharge end of the shell.

9. A distilling apparatus comprising a fur- 65 nace having a heating-chamber, a retort hav- 70 ing a revoluble shell extending through the heating-chamber, the shell being closed by fixed heads, a delivery-conveyer extending through one head to deliver the material to be treated to the receiving end of the shell, a 75 discharging-conveyer having a trough and a conveyer-screw therein, the trough extending through the other shell-head a distance into the discharge end of the shell, the bottom of the trough being perforated, lifting-plates se- 80 cured to the shell at the discharge end, to lift the material and deliver it to the said trough, a pipe for carrying off the liquid from the discharge end of the shell and extending through the head at this end of the shell, and means 85 for feeding the material in the shell from the receiving end to the discharge end.

In testimony whereof I have signed my name to this specification in the presence of two sub-scribing witnesses.
